UNITED STATES PATENT OFFICE.

EARL A. BARNES, OF OELWEIN, IOWA.

AUTOMATIC VALVE MECHANISM.

1,187,125.

Specification of Letters Patent. Patented June 13, 1916.

Application filed July 19, 1915. Serial No. 40,537.

To all whom it may concern:

Be it known that I, EARL A. BARNES, a citizen of the United States, and resident of Oelwein, in the county of Fayette and State of Iowa, have invented certain new and useful Improvements in Automatic Valve Mechanism, of which the following is a description, reference being had to the accompanying drawing, which forms a part 10 of my specification.

My invention relates to valve mechanism especially intended for use in connection with a squirt-hose employed on locomotives for the purpose of wetting down the deck 15 and the coal.

The object of my invention is the provision of mechanism, the operation whereof will be entirely automatic, so that the hot water or steam, or both, obtained from the 20 locomotive-boiler, will only be permitted to flow through the squirt-hose when the latter is held under tension and in position to properly direct the stream; the flow into and through the hose being instantaneously and 25 automatically shut off as soon as the tension on the hose is relaxed, by releasing the squirt-hose, so that the danger of scalding the engine-men or operator will be entirely eliminated.

30 In the drawing: Figure 1 illustrates the application of my invention, in side elevation to the fire-box end of a locomotive boiler; the cab-end of a locomotive and the forward or open end of a tender being shown to illustrate the adaptation of my invention. Fig. 2 is a longitudinal, vertical, 35 sectional view of the valve-mechanism. Fig. 3 is a plan view of the valve-mechanism with the operating mechanism removed, illustrating, partially in dotted lines, a method 40 of securing the valve to the boiler. Fig. 4 is a detail plan view of a portion of the valve-operating and hose-clamping mechanism.

45 In the particular exemplification of my invention, as disclosed in the drawing, the device is shown applied to the fire-box end of a locomotive-boiler; a portion of the cab or deck of the locomotive and a portion of 50 a tender being shown in Fig. 1 in order to illustrate a method of application.

The invention comprises a valve 10, which is preferably connected by means of pipe 11 to the delivery end of the injector

12, usually located at the side of the boiler 55 as shown; it being understood, of course, that the injector may be of the usual constructions employed in locomotive practice.

As the injector forms no part of my invention, a detailed description of the construction and operation thereof need not be entered into.

The valve part of the mechanism consists of the body portion 13, provided with the inlet port or passage 14 and the outlet port 60 or passage 15, see Fig. 2. The inlet and outlet ports or passages are separated by the intermediate, horizontally disposed diaphragm or wall 16 provided with the communicating port 17. The inlet side of the 70 diaphragm 16 is arranged to provide a valve-seat for the valve 18, arranged to move in a manner perpendicular to the wall or diaphragm 16. The valve 18 is preferably provided on both surfaces with the 75 guide-stems 19 and 20, which are slidably mounted in the cap-members 21 and 22, respectively. The cap-member 22 is provided with a hole extending part way there- 80 through, namely to a distance slightly beyond the point to which stem 20 normally extends into said opening, as clearly shown in Fig. 2; thus permitting vertical movement of the valve 18 and its stems to a pre- 85 determined extent. The body portion 13 of the valve is preferably tapped so as to provide the threaded openings to receive the threaded shank portions of cap-members 21 and 22, which also close the inner ends of the passages 14 and 15. These cap-members 90 21 and 22 enable the valve 18 to be readily put into place and also make the valve easily accessible for repairs, and the like, as will be apparent from the drawing.

The stem 20 is preferably encircled by the 95 coil-spring 23, which bears against the bottom of valve 18 and the inner end of cap-member 22, and normally tends to maintain valve 18 on its seat when the pressure of the fluid in passage 14 has been removed, by 100 reason of the shutting off of fluid through pipe 11 and into passage 14. As the stem 19 of the valve 18 is adapted to extend entirely through the cap-member 21, I prefer to enlarge the opening through which stem 105 19 passes, at the outer end thereof, in order to receive the packing ring 24, which is held in place by the stuffing-box 25, which screws

into the enlarged outer end of the stem-passage, see Fig. 2, and forms a fluid-tight connection.

The cap-member 21 is provided with an arm 21^a, the outer end whereof is preferably bifurcated and receives a lever 26, which is pivotally secured at 27 to the arm 21^a. The inner or short arm 26^a of lever 26 is arranged to extend across the top of stem 19, 10 which is preferably rounded as shown in Fig. 2, so as to afford sliding contact with the lever. The outer or long arm of lever 26 has a clamp-member 28, preferably pivoted thereto, as shown at 29, while the other 15 end of clamp-member 28 is intended to be securely fastened in any suitable manner, as, for example, by means of bolt 30. The end of lever 26 and the clamp-member 28 are similarly bowed, as shown in Fig. 4, to encircle the squirt-hose 31, see Fig. 1; the bowed or hose-receiving portions of the lever and clamp-member 28 are, of course, made so as to provide a substantially circular passage, smaller in diameter than the 20 diameter of the hose, in order to afford a good grip on the hose 31, so as to prevent the hose slipping therethrough.

The inlet passage 14 is preferably tapped, as shown in Fig. 2, to receive the connection 32, for effecting proper connection with pipe 11, see Fig. 1; and the outlet passage 15 is also shown tapped to receive the threaded end of the nipple 33, see Fig. 2. The nipple 33 is adapted to enter the end of 25 hose 31 in order that a suitable clamp, as shown, for example, at 34 in Fig. 1, may be employed for securely clamping the hose onto the outlet end of the valve. The lever 26 is clamped to hose 31, so as to allow slight 30 play of hose intermediate of the clamping point of the lever and point of connection with the nipple 33, as clearly shown in Fig. 1. This will allow the hose 31 to be lifted so as to exert an upward pull on the long 35 arm of lever 26 without exerting a pulling strain on the inner end of the hose 31 where it is coupled to the nipple 33.

The squirt-hose and its valve-mechanism are preferably located near the engine-deck; 40 the valve being secured at any convenient point by means of a suitable bracket, as, for example, illustrated in Fig. 3, where the bracket is shown in dotted lines and clamped to the valve 10 by means of the stud-bolts 45 35; the bracket being preferably secured to the back-head of the boiler. It will be understood, of course, that any suitable method of securing the valve in place may be employed; the valve, however, being preferably located at a point that will enable an 50 upward pull on the hose 31, during the ordinary or proper use of the squirt-hose. The connection 36 supplies water from the tender 37 to the injector 12; the flow of water 55 being induced through the action of steam

supplied from the boiler to the injector 12 by means of pipe 38, in the usual manner.

It is evident from the construction shown and described, that when the engine-crew desire to wet the coal or the deck, or both, 70 the free end of squirt-hose 31 is grasped and a slight upward pull exerted thereon; this will cause lever 26 to press downwardly on stem 19 and move valve 18 off its seat against the action of spring 23 and the pressure of 75 the steam and water in the inlet passage 14 of the valve; it being understood, of course, that the injector is open.

It is evident that as soon as tension on the 80 hose is released, the upward pull on lever 26 will thereby be released, so that the force of the fluid in passage 14, together with the action of spring 23, will immediately return valve 18 to its seat and shut off the flow of water and steam, either one or both, 85 through the squirt-hose 31.

With my improved construction, the action of the squirt-hose is entirely automatic, 90 so that the possibility of serious injury to the engine-men, due to scalding with hot water, will be entirely eliminated.

The automatic operation of my device will cause the valve to be immediately closed, should the hose blow or slip off of the nipple-connection, as the operator may drop the 95 hose, which will release tension on the hose, and cause the outflowing fluid, assisted by the spring, to close the valve, and thereby shut off the further flow. With the constructions heretofore employed, the fact that 100 the injector may have previously been closed, has induced the engine-men to forget to close off the usual globe-valve employed, with the result that when the injector was again opened, steam and hot water 105 was allowed to escape into the cab through the squirt-hose, thereby causing serious injury to the crew. Again, with the construction heretofore employed, the globe-valve has usually been located down near the deck, 110 where it has frequently been accidentally kicked or rubbed open by the crew while climbing on or off the deck. Furthermore, with the previous constructions where the globe-valve was located down near the deck, 115 if the squirt-hose should burst or slip off of the nipple, the flow of hot water and steam could only be shut off by shutting off the injector or by manipulating the valve, which necessitated coming into contact with the 120 hot water and steam in order to close the valve.

With my improved construction, should the injector be shut off, thereby cutting off the flow of steam and water to the valve 18, 125 no injury can result, because the spring 23 will force the valve to its seat, so that steam and water could not enter the squirt-hose when the injector is again opened.

The operating lever 26 is preferably un- 130

attached to the valve-stem, so that the long arm of the lever may have considerable freedom of movement while the squirt-hose is not in use, without moving the valve from 5 its seat.

The advantages of my invention will be readily apparent; and I have shown and described what I believe to be the simplest and best form of my invention, but the same 10 may be modified in certain respects without, however, departing from the spirit of my invention, and I do not wish to be understood, therefore, as limiting myself to the exact construction shown and described.

15 What I claim is:—

1. Mechanism of the class described, comprising a valve-casing provided with inlet and outlet passages, the inner ends whereof are separated by a diaphragm or wall provided with a port, cap-members removably secured in the valve-casing whereby access to the inner ends of both of said passages may be had, one of the cap-members being provided with an opening extending there- 20 through while the other cap-member is provided on its inner surface with a socket, a spring-controlled valve mounted in the inlet passage and provided with oppositely disposed plungers or stems, one plunger or 25 stem extending through the opening in the one cap while the other stem extends into the socket of the other cap, a stuffing-box secured to said first mentioned cap and surrounding the valve-plunger or stem, a lever 30 fulcrumed on the cap-member through which the valve stem extends so as to have its short end in contact with the outer end of said plunger or stem, a squirt-hose secured to the outlet passage of said valve- 35 casing, and means whereby said squirt-hose 40

is clamped to the long end of said lever so that lifting of the squirt-hose will cause said lever to move said valve off its seat.

2. Automatic valve mechanism, comprising a valve-casing, having an inlet and an outlet passage, the inner ends of said passages being separated by a diaphragm or wall provided with a port, the inlet passage having communication with a source of water-supply while the outlet passage is provided with a squirt-hose, a reciprocatingly mounted valve located in the inlet passage and closable through the action of the fluid in said inlet passage, a spring for yieldingly maintaining said valve on its seat, cap-members removably secured in the valve-casing whereby the inner ends of both of said passages are closed, plungers or stems secured to opposite sides of the valve and slidably mounted in said cap-members, one of said stems being adapted to extend entirely through one of the cap-members, said last-mentioned cap-member being provided with an arm, a stuffing-box secured to 60 said last mentioned cap-member and surrounding the valve-plunger or stem extending therethrough, a lever pivotally mounted on said arm so as to have its short end in contact with the outer end of said protruding valve-stem, and means whereby the opposite or long end of said lever is clamped to said squirt-hose so that an upward pull exerted on the squirt-hose will cause said lever to oscillate and force the valve off its seat against the action of the fluid in said 65 inlet passage.
